PUNCH RETAINER

Carl Birger Wallman, Detroit, Mich.

Application January 30, 1933, Serial No. 654,274

3 Claims. (Cl. 279—77)

The invention relates to improvements in punch locking device for quick release punch retainers which allows the removal of punches which have been dulled or broken, and the objects of the improvements are;

First, it affords the absolute control of all parts of the said locking device, that is, there are no loose or floating details which interfere with the removal or insertion of the punch,

Second, it affords facilities for the operator to make the change of punches without the aid of any tools or equipment, and

Third, it enables the diemaking in aligning the punch and die following construction to manipulate the punches so as to inspect them in relation to holes in the die without the removal of the locking device.

These and other objects will become apparent in the description below, in which characters of reference refer to like named parts in the drawing.

One form of the invention is illustrated in the accompanying drawing in which Figure 1 displays the device in a locked position for holding the punch. The cross sections are of detail 1 through the line A A and detail 7 through the line B B of Figure 2.

Figure 2 is a plan or top view of punch pad 1, punch 8, and entire locking device, in which the locking device is shown in a released position.

Figure 3 is a view similar to Figure 1 with same cross sections omitting punch holder 9 and backing plate 2, in which is shown the locking device in released position with punch 8 partially removed.

Figure 4 is same view as Figure 3 with punch 8 entirely removed and locking device in a retarded position, which is position of locking device when diemaking is making inspection of alignment of punches with die following construction of punch and die.

Block 1 known as punch pad has punch hole 10 perpendicularly through its thickness for receiving the punch 8, said punch 8 being slotted to receive locking block 3. A locking block pocket 11 is cut in pad 1 at right angles to hole 10 with bottom at an angle to side of hole 10 and opening up into punch hole 10. Pad 1 has another hole 12 at an angle in the angular bottom of pocket 11 in which is placed guide 4.

Release pin hole 13 also in pad 1 is parallel to punch hole 10 and parallel to the side of pocket 11 and extends through pad 1. In pad 1 stock is cut away between upper end of release pin hole 13 and locking block pocket 11 thus forming release pin slot 15 through

which L shaped release pin 5 can be put in place. Release pin hole 13 is enlarged at end opposite pocket 11 to provide a pocket 14 for spring 6. Locking block 3 is a sliding fit in locking block pocket 11 and has locking block hole 16, which locking block hole 16 is a slip fit for the short leg of the L shaped release pin 5, said release pin 5 controlling the movement of the locking block 3. Locking block 3 is made irregular in outline, so that a rotating motion of the locking block 3 is obtained by reason of the reciprocating motion of the release pin 5 and locking block's relative position to guide 4. A spring 6 is placed on release pin 5 and in spring pocket 14 and retained by means of a release button 7 which is riveted on to release pin 5. A backing plate 2 is inserted between the punch pad 1 and the punch holder 9 of which punch holder 9 a fragment is shown.

Referring to Figure 1 in which punch 8 is locked rigidly by means of locking block 3, locking block 3 is brought into position by force of spring 6 being released and controlled by guide in the form of an inner stop or thrust member 4. Pressure is exerted on the punch 8 in an upward direction against backing plate 2 when said locking block 3 is forced into space between the angular bottom of the locking block pocket 11 and the upper side of slot 17 in punch 8. The angular bottom of locking block pocket 11 and the upper side of punch slot 17 not being parallel but the punch slot 17 opening away from the angular bottom of locking block pocket 11 forming a tapered opening in which locking block 3 acts as a wedge. Referring to Figure 3 in which is shown the locking device in released position, the locking block 3 is moved upward by means of pressure exerted on the release button 7 and the said locking block 3 being moved out of the path of the punch 8 by the guide 4. This block 3 cannot be moved upward by pressure on the outer end thereof of the punch 8, as the inner end of the block engages the thrust member or guide 4 which prevents such pressure being transmitted to the pin 5 in the hole 16.

Referring to Figure 4 it shows the locking block 3 in a retarded position. This is the position in which the device is placed when assembled with the punch and die. It is released by pressure exerted on release pin button 7 by the die maker after the test for alignment of the punches in the die. It will be noticed that this position is accomplished by swinging the locking end of the locking block 3 away from the punch 8.

I am aware that prior to my invention punch

locking devices have been made with locking mechanisms for the release of punches. I therefore do not claim such a combination broadly; but I claim:

5. 1. In a device of the class described, a pad bored to receive a tool shank, the wall of said bore being recessed, a tool-locking block having vertical and rotary movement in said recess, guide means inclined towards the receiving end of the bore of said pad and engaging one end of said block, further guide means inclined towards the other end of said bore and engaging the opposite end of said block, and manually operable means for effecting vertical movement of said block in said recess whereby positive rotation of said block in one or other direction by said guide means is effected.
2. In a device of the class described, a pad bored to receive a tool shank, the wall of said bore being recessed, a tool-locking block having vertical and rotary movement in said recess, guide means inclined towards the receiving end of the bore of said pad and engaging one end of said block, a thrust member inclined towards the other

end of said bore and engaging the opposite end of said block, and manually operable means for effecting vertical movement of said block in said recess whereby positive rotation of said block in one or other direction is guided by said guide means and said thrust member.

80

3. In a device of the class described, a pad bored to receive a tool shank, the wall of said bore being laterally recessed to provide an inclined surface directed towards the receiving end of said bore, a manually operable vertically movable plunger entering said recess, a tool-locking block in said recess fulcrummed intermediate of its length on the inner end of said member, said block being swingable to a position projecting into the bore of said pad in one position of said plunger and swingable to a latched position within said recess in the other position of said plunger, resilient means tending to move said plunger to its first-mentioned position, and a thrust member engaging the inner end of said block to resist pressure of a tool thereon when said block is in its tool-locking position.
